United States Patent

Des. 239,439
Patented Apr. 6, 1976

239,439

WRISTWATCH

Harriet R. Davis, 2408 California St. NW.,
Washington, D.C. 20008

Filed June 17, 1974, Ser. No. 480,015

Term of patent 14 years

Int. Cl. D10—02

U.S. Cl. D10—39

FIG. 1

FIG. 2

FIG. 1 is a top plan view of a wristwatch showing my new design (the rear being plain and conventional); and

FIG. 2 is a right side elevation view thereof (the opposite side being a mirror image thereto without the crown).

I claim:

The ornamental design for a wristwatch, as shown and described.
